(57) **CLAIM**

I claim the ornamental design for a remote control, as shown and described.

DESCRIPTION

FIG. 1 is a top right perspective view of a remote control showing my new design;

FIG. 2 is a bottom right perspective view thereof;

FIG. 3 is a left side view thereof;

FIG. 4 is a top view thereof;

FIG. 5 is a right side view thereof;

FIG. 6 is a bottom view thereof;

FIG. 7 is a front view thereof; and,

FIG. 8 is a rear view thereof.

The broken lines showing buttons and a battery door in the figures depict portions of the remote control that form no part of the claimed design.
